[57] CLAIM

The ornamental design for a page and line finder, as shown and described.

DESCRIPTION

FIG. 1 is a plan view of one side of the page and line finder;

FIG. 2 is a plan view of the opposite side of the page and line finder;

FIG. 3 is an edge view of the novel page and line finder, each edge being identical, only one thereof is shown; and,

FIG. 4 is an end view of the page and line finder, according to my design, each end being identical, only one thereof is shown.

FIG. 1

FIG. 2

FIG. 3

FIG. 4
